The ornamental design for a band-aid, as shown and described.

DESCRIPTION

FIG. 1 is a top view of the band-aid, showing my new design;

FIG. 2 is a bottom view thereof;

FIG. 3 is a front elevational view thereof;

FIG. 4 is a rear elevational view thereof;
FIG. 5 is a cross-sectional view thereof, taken along line 5—5 of FIG. 1;

FIG. 6 is a side elevational view, the opposite side being identical thereto; and,

FIG. 7 is an enlarged fragmentary view of the section indicated by the numeral 7 on FIG. 5.
